EYELASH CURLER

William R. Tuttle and Charles W. Stickel, Rochester, N. Y., assignors to The Kurlash Company, Inc., Rochester, N. Y., a corporation of New York

Application November 24, 1934, Serial No. 754,664

9 Claims. (Cl. 132—32)

This invention relates generally to eyelash curlers wherein the upper fixed jaw and the lower movable or curling jaw cooperate in the same plane in the crimping or curling operation.

5 More specifically the invention relates to a type of eyelash curler described in United States Letters Patents Nos. 1,699,084 and 1,904,575 and wherein provision is made for the removal of the operating piece of the lower and movable curling

10 jaw of the curler above described.

The main object of the invention is the provision of a replaceable member adapted to cooperate with the lower movable or curling jaw such that the eyelash curler can be said to have a removable lower jaw for purposes of replacing the operative portions thereof resulting from wear and tear and destruction of the operative rubber member therein.

Another object of the invention is the provision of a lower movable or curling jaw capable of disassembly for purposes of feeding new operative members to the said curler structure.

These objects and other incidental ends and advantages of the invention will hereinafter appear in the progress of the disclosure and as pointed out in the appended claims.

The accompanying drawings form a part of this specification and show a preferred form of the invention and a modified form thereof, and in which drawings corresponding reference characters designate corresponding parts throughout the several views.

According to the drawings, Figure 1 is a perspective view of the approved eyelash curler.

Figure 2 is a sectional view along the plane 2—2 thereof showing the embodiment of the invention herein.

Figure 3 is a sectional view of Figure 2 along the plane 3—3 thereof.

40 Figure 4 is a view in perspective of a cartridge member insertable in the lower movable or curling jaw of the curler herein.

Figure 5 is a rear view of Figure 1 when the eyelash curler is in closed and operative condition.

45 Figure 6 is an exploded view similar to Figure 3 showing the method of insertion of the cartridge in the lower movable or curling jaw.

Figure 7 is a rear view of a modification of the structure shown in Figure 1 equivalent to the rear view shown in Figure 5.

50 Figure 8 is a perspective view of a modification of Figure 1 being shown without a cartridge member.

Figure 9 is a sectional view along the plane 9—9 of Figure 8 but showing an inserted cartridge

member in the lower movable or curling jaw thereof.

Figure 10 is an exploded view similar to Figure 6 but of a modified construction thereof.

Figure 11 is a view in perspective of a cartridge 5 similar to Figure 4 except for a modification.

In accordance with the invention and in accordance with the preferred form and modification of said preferred form, the curler is provided with a supporting lever rigidly connected with 10 the upper jaw and forms a support for the lower movable jaw, said supporting lever being constructed preferably of a similar piece of wire doubled upon itself to form a lower or outer handle arm and an upper supporting arm. The lower 15 arm of the supporting lever is provided with two longitudinal bars 13 which are juxtaposed or arranged together and connected at their outer ends by a finger receiving loop 14—31. The upper arm of the supporting lever is composed of 20 two diverging side bars 15 which are offset vertically to form upward parallel portions 17.

Bars 17 at the upper ends thereof are provided with a cross piece 10 to serve as the upper or curling jaw. The lower movable jaw is mounted on 25 the upper arms or bars 17 of the supporting lever so as to slide lengthwise thereon toward and from the fixed upper jaw 10. The lower movable jaw designated by numeral 11 is comprised of a channel member having sleeves 19 at the opposite ends 30 thereof, the said sleeves being slidably mounted on the guide bars 17 of the supporting lever and operate to maintain the two jaws in parallelism with each other as the same are moved toward and from each other.

35 It is to be observed that the curvature of fixed jaw 10 and movable jaw 11 is adapted to correspond with the curvature of the upper eyelid.

The movement of the lower movable jaw 11 is effected preferably by an operating lever made 40 from a single piece of wire and doubled upon itself. The lower or outer arm of this operating lever comprises two longitudinal bars 20 which are juxtaposed and connected at their outer ends by means of a finger loop 21—32, 45 and two upper or inner bars 22 which are also arranged close together or juxtaposed.

The upper and lower arms of the operating lever are arranged at an angle relatively to each other so that the same as a whole has the 50 form of an elbow lever and it is preferably pivotally connected with the supporting lever by inserting the operating lever between the two bars of the supporting lever and running a rivet 23 horizontally and transversely throughout the 55

several bars of the two levers at the point of crossing or intersection of the same as shown in Figures 1, 5, 7, and 8.

In order to provide a wide bearing surface of these levers against each other at the place where they cross each other, those parts of the same adjacent to the pivot 23 connecting the same are flattened, as shown at numerals 24 and 25, thereby guiding these levers relative to each other and maintaining them in the proper position as they turn about the axis of the pivot pin 23.

The link connecting the upper arm of the operating lever with the lower jaw is preferably constructed of a single piece of wire doubled upon itself so as to form two side bars, the lower parts 26 of which are arranged close together and are connected by a bend or wrist pin 27 which passes through an opening 28 in the upper arm of the operating lever while the rods or upper parts 29 of the link diverge upwardly and are connected in any suitable manner with the channel 11 of the lower jaw, preferably by passing each bar of this link through an opening in the bottom of the channel and riveting the same against the inner side of this channel as shown at 30 in Figures 2 and 9.

The essence of the invention herein resides in the adaptation of the lower and movable jaw member 11 such that the operative member thereof is removable and insertable by means best designated by the expression "cartridges".

In the form shown in Figures 1-6 inclusive, the lower jaw member 11 is of channel form and U shaped preferably in cross section to admit the insertion therein of a cartridge 16 having outwardly extending and upper edge flanges 16. The said cartridge member 16 is adapted to frictionally engage with the channel of the lower jaw 11 with the flanges 16' thereof superposing the upper edges of the channel 11. The cartridge 16 is adapted to be removable from channel 11 by engaging with the fingers the edges of the flanges 16' and bearing upward pressure.

The cartridge 16 being preferably of the same cross sectional contour as channel 11, is adapted to receive the rubber or elastic strip member 12 having a central and longitudinal groove 12' on the upper face thereof with which groove the operative edge of the fixed jaw member 10 cooperates in the crimping operation. It thus can be seen that a curler is provided having means to remove the operative portion of the lower jaw bodily from the curler and inserting a new operative portion whenever necessary without the necessity of disassembling the curler structure.

In Figures 7-11 inclusive, a modified form of a lower jaw 11 is shown wherein the lower jaw is designated by numeral 33, the said lower jaw 33 not being connected to and being short of reaching parallel arm members 17. Lower jaw 33 is comprised of a channel member being preferably U shaped in cross section and is provided with a cartridge 34 having outwardly extending flanges 34' at the upper edges thereof, the said cartridge 34 being equivalent to cartridge 16 except for projecting strips 35 extending from the inner surfaces of the rear vertical wall of the cartridge member 34. These strips 35 are adapted to be curled around the parallel bars 17 to form sleeves equivalent to sleeves 19 of Figure 1, as best shown in Figure 9.

Whenever it is desirable under this modified

form to replace the elastic strip 36 having a longitudinal and central groove 36' on the upper face thereof, it is merely necessary to uncurl curled portions of projecting strips 35 about the parallel bars 17.

It is to be noted that the projecting strips 35 are affixed to the inner surface of the rear wall of cartridge member 34 by any known means such as soldering or brazing, it being understood that the said projecting strips 35 may be integral with and merely extensions of the rear wall of the said cartridge 34. Except for these projecting strips 35, cartridge 34 is identical with cartridge 16, the elastic member in the said cartridge 34 being equivalent to elastic member 12 of Figures 1-6 inclusive.

From the foregoing description, it can be seen that the cartridge idea as applied to United States Patents Nos. 1,699,084 and 1,904,575 virtually amounts to a transformation of the structure 20 shown therein wherein the permanently attached and movable lower jaws become removable and replaceable as respects the operative member thereof, to wit, the elastic or rubber strips 12 and 36.

We wish it understood that minor changes and variations in the shape, structure and integration of the several parts, together with relative positions thereof may all be resorted to without departing from the spirit of the invention and without departing from the scope of the appended claims.

We claim:

1. In an eyelash curler comprising two relatively and vertically movable jaws curved to fit an eyelid and to receive eyelashes between them and wherein the upper jaw is provided with a lower operative edge, a lower jaw having an upwardly opening channel, a second channel member removably engageable with the said upwardly opening channel, and a removable elastic strip in said second channel member for engagement with the operative edge of the upper jaw.

2. In a device of the class described, the combination of an upper and a lower jaw, means for operating said jaws one with respect to the other, said lower jaw provided with a channel, a cartridge seated in said channel and provided on its upper edge with flanges, whereby the operator can grip said flanges and quickly remove said cartridge from said channel, and a yieldable strip in said cartridge.

3. In a device of the class described, the combination of an upper and a lower jaw, means for operating said jaws one with respect to the other, said lower jaw provided with a channel, a cartridge seated in said channel and provided with horizontal outwardly-extending flanges normally resting on the edges of said channel, and a yieldable strip in said cartridge.

4. In a device of the class described, the combination of an upper and a lower jaw, means for operating said jaws one with respect to the other, said lower jaw including two channeled units nested together, and one of said units provided with yielding means adapted to engage the upper jaw.

5. In a device of the class described, the combination of a primary lever unit provided with an upper jaw, an auxiliary lever unit movably mounted on and cooperating with said primary lever unit, a lower jaw including a cartridge thereon, mounted on said auxiliary lever unit, means connecting only the cartridge to said pri-

mary lever unit, and yieldable means in said cartridge.

6. In a device of the class described, the combination of a primary lever unit provided with an upper jaw, an auxiliary lever unit movably mounted on and cooperating with said primary lever unit, a lower jaw mounted on said auxiliary lever unit, a cartridge provided with projecting strips, said cartridge seated in said lower jaw, said projecting strips engaging portions of said primary lever unit, and yieldable means carried by said cartridge.

7. In a device of the class described, the combination of a primary lever unit provided with an upper jaw, an auxiliary lever unit movably mounted on and cooperating with said primary lever unit, a lower channeled jaw between portions of said primary lever unit and mounted on said auxiliary lever unit, a cartridge provided at its ends with projecting strips, said strips around portions of said primary lever unit, whereby said lower jaw is secured in position, and a rubber strip seated in said cartridge.

8. In a device of the class described, the combination of a primary lever unit provided with

an upper jaw, an auxiliary lever unit movably mounted on and cooperating with said primary lever unit, a lower channeled jaw positioned at its ends between portions of said primary lever unit and mounted on said auxiliary lever unit, a channeled cartridge seated in said lower channeled jaw, said cartridge having projecting strips extending outwardly in a vertical plane from the ends of the inner wall, said projecting strips bent around to form sleeves upon portions of said primary lever unit, and a flexible strip seated in the channel of said cartridge, substantially as shown and described.

9. In a device of the class described, the combination of a primary lever unit provided with an upper jaw, an auxiliary lever unit pivotally mounted on said primary lever unit, said auxiliary lever unit including an upper elbow link having its upper and lower portions formed in two planes, whereby a more even thrust upwardly is obtained, and a lower jaw fastened to the upper end of said elbow link, substantially as shown and described.
